UNITED STATES PATENT OFFICE

ALBERT GODFREY GREENE, OF PROVIDENCE, RHODE ISLAND, ASSIGNOR TO REVERE RUBBER COMPANY, OF PROVIDENCE, RHODE ISLAND, A CORPORATION OF RHODE ISLAND

DESIGN FOR A BATHING CAP

Application filed November 2, 1929. Serial No. 33,264. Term of patent 14 years.

To all whom it may concern:

Be it known that I, ALBERT GODFREY GREENE, a citizen of the United States, residing at Providence, county of Providence, State of Rhode Island, have invented a new, original, and ornamental Design for Bathing Cap, of which the following is a specification, reference being had to the accompanying drawing, forming part thereof, wherein the figure is a side view of a bathing cap showing my new design.

I claim:

The ornamental design for a bathing cap, as shown.

Signed at Providence, county of Providence, State of Rhode Island, this 25th day of October, 1929.

ALBERT GODFREY GREENE.
